US00D810478S

(12) **United States Design Patent** (10) Patent No.: **US D810,478 S**
(45) Date of Patent: **** Feb. 20, 2018**

(54) **DISPLAY STAND COMPONENT**

- (71) Applicant: **Apple Inc.**, Cupertino, CA (US)
- (72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Sung-Ho Tan**, San Francisco, CA (US); **Clement Tissandier**, San Francisco, CA (US); **Eugene Antony Whang**, San Francisco, CA (US); **Rico Zörkendorfer**, San Francisco, CA (US)
- (73) Assignee: **Apple Inc.**, Cupertino, CA (US)
- (**) Term: **15 Years**
- (21) Appl. No.: **29/571,404**
- (22) Filed: **Jul. 18, 2016**
- (51) LOC (11) Cl. **06-06**
- (52) U.S. Cl. **D6/682**
- USPC **D6/682**

(57) **CLAIM**

The ornamental design for a display stand component, as shown and described.

DESCRIPTION

FIG. 1 is a top front perspective view of a display stand component showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the display stand component and environment that form no part of the claimed design.

1 Claim, 7 Drawing Sheets
